UNITED STATES PATENT OFFICE

FREDRICK A. OLMSTEAD, OF CLEVELAND, OHIO, ASSIGNOR TO THE CHAIN PRODUCTS COMPANY, OF CLEVELAND, OHIO, A CORPORATION OF OHIO

CHAIN TOOL

Application filed October 27, 1926. Serial No. 144,460.

This invention relates to chain tools and particularly to tools intended for opening, closing and cutting chain links, especially such as are commonly employed in chains 5 of automobile non-skid tire devices; and the invention comprises generally improvements in the device disclosed in my copending application Serial No. 117,100, filed June 19, 1926, now issued as Patent No. 1,732,654, 10 dated October 22, 1929.

The above named operations are frequently necessary in servicing chains of the type to which reference has been made and numerous tools have been devised for the purpose, both hand tools of a strictly portable nature, and tools adapted to be secured upon a bench or the like as is the tool described in my copending application identified above. In the construction of all of such tools are 15 necessarily incorporated a plurality of link manipulating members intended for selective use, although usually all of these members are closed or opened in their normally functioning manner by relative movement 20 of the pair of operating members customarily provided. In an organization such as described, owing to carelessness or intended rapidity of operation of the tool, occasionally a portion of a chain not intended to be 25 worked upon will find a position between a pair of the link manipulating members other than the pair selected and the chain is thus accidentally damaged as by deformation or even in some cases severance.

It is the object of my invention, therefore, 30 to produce a chain tool wherein closing of the most dangerous portion of the tool, that is the cutting jaws, is produced by a motion of the operating portion of the tool, that is 35 the handled member or members, which is distinct from that required for effecting the remaining of the several functions of the tool. Another object of my invention is to produce a conformation of the various link 40 manipulating members that they shall be capable of functioning with the utmost efficiency. A still further object of my invention is to so arrange the several parts of the tool that all of the operations for which the 45 tool is designed may be accomplished with

the greatest convenience and safety to the operator, and to this end, in which all of the link manipulating or working members shall be positioned within easy accessibility and view of the operator from a common direction, as in front of the tool. A still further object of the invention is to produce by the 55 said arrangement of parts a suitable leverage whereby great ease of manipulation will result.

The exact nature of my invention will be 60 apparent from the following description taken in connection with the accompanying drawings in which Fig. 1 is a side elevation of the tool showing a link in position thereon to be closed in secured relation with a second link which appears; Fig. 2 is a front end elevation of the tool; and Fig. 3 is a view 65 along the plane of line 3—3, Fig. 1.

The tool comprises primarily a pair of 70 jaws consisting of a base member 1, adapted in the example chosen for illustration to be secured upon a bench or the like, and a handled operating member 2 comprising a long arm, a bend, and a short arm or half-round hook in pivotal connection with the base at 3, and thus attached for relative movement therewith. The member 2 is thus of a general L-shape and close to the bend carries a bill 4 adapted for cooperation with 75 a similar bill 4' mounted upon the base as indicated, and a member 5 adapted for cooperation with a member 5' secured upon the base. Within the base is secured a cutting 80 jaw 6 adapted for cooperation with a similar cutting jaw 6' pivotally mounted upon the base at 7 and connected by the links 8 with the member 2, as indicated.

The bills 4, 4' are of generally conical conformation but provided each with a cylindrical surface 9, 9' concentric with the point 3 so that the bills are adapted as they are closed one upon the other to cooperate to present a generally cylindrical outer surface of increasing diameter, whereby an eye of a link positioned upon the member 4' will upon 95 forward and downward movement of the lever 2 be spread and thus opened.

The upper face of the member 5' as indicated is of conformation to receive a chain 100

link A and position the same in the plane of the members 1 and 2, the longitudinally extending upstanding portions 10 laterally positioning the link, the upstanding curved portion 11 longitudinally positioning the link, and the whole supporting the link clear of the bill 4'. The member 5 is also provided laterally with positioning extensions 12; the whole arrangement being such that 10 action of the member 5 upon forward motion of the lever 2 against the link A so positioned on the member 5' will effect closing of the link in secured relation with the link B. The forward face of the member 5' is cut away as 15 indicated to clear a link positioned upon the bill 4' and to clear the base portion of the bill 4 when closed thereupon.

The arrangement of the jaws 6 and 6' is such that the jaws are closed when the lever 20 2 is upstanding, as in Fig. 1, and therefore when the members 4, 4' and 5, 5' are most widely separated, this being the relation of the parts when chain links to be worked upon are positioned upon either of the members 25 4' or 5'. The links 8 extend between pivotal connections at the points 13 and 14 with the lever 2 and the jaw 6' respectively, the arrangement being that of a toggle such that the points 3 and 14 are most nearly in line 30 with the point 13 when jaws 6 and 6' are closed, whereby the jaws are closed by upward movement of the member 2 and with increasing leverage. The working edges of 35 the jaws 6 and 6' are slightly rounded in section as indicated in Fig. 2, whereby they are capable of crunching through the case hardened surface of a link placed between them and severing the link by a squeezing action.

What I claim is:

- 40 1. A bench tool for severing and manipulating the links of tire chains and the like comprising a base adapted to be secured to a suitable support, relatively movable severing jaws extending and opening beyond the base, relatively movable link spreading and closing jaws above the severing jaws and opening in the same direction as the severing jaws, a single operating member having movement in the plane of the jaws, operative 45 connections between said member and the link spreading and closing jaws causing them to close with movement of the operating member in one direction, and connections between the operating member and the severing 50 jaws to cause them to open with the closing movement of the other jaws, whereby when one set of said jaws is opening, the other is closing and vice versa.
- 55 2. In a chain tool, a base member adapted to be secured on a support, a link working member mounted upon said base, an operating lever pivoted on said base behind said link working member to swing forwardly 60 and carrying a second link working member

adapted to close upon the first named link working member as the lever is swung forwardly, and a pair of relatively movable cutting jaws mounted on the base member below said link working members and presenting their cutting portions forwardly, and operating means extending from the cutting jaws to said lever and connected thereto on the proper side of its pivot so that said cutting jaws close as said lever is moved rearwardly.

In testimony whereof I hereby affix my signature.

FREDRICK A. OLMSTEAD.
